ABSTRACT

Lamp triggering circuits for use in triggering selected lamps within a plural lamp array in a high-speed fashion and having circuit connection means adapted to prevent false triggering of lamps adjacent to those selected to fire.

LAMP TRIGGERING CIRCUIT

The present invention relates to triggering circuits for lamp arrays, and more particularly to a novel triggering circuit for triggering and firing only selected lamps within an array and for preventing false firing of those lamps adjacent to the lamps which have been fired.

BACKGROUND OF THE INVENTION

There exist a wide variety of applications wherein it is desired to fire selected lamps within a lamp array, which operations are performed at high-speed and require accurate, positive firing of only those lamps selected to be triggered.

One particular application of such lamp arrays in trigger circuits is set forth in copending application, Ser. No. 801,635, filed Feb. 24, 1969, and assigned to the assignee of the present invention. The above-mentioned copending application teaches a high-speed non-impact printer in which a lamp array which may be comprised of more than 100 lamps arranged in closely spaced fashion are selectively triggered as and when certain characters provided upon the periphery of a revolving drum, move into a position in which the character they represent and position on the line at which the character is to be printed is called for. Since the drum rotates at a relatively high-speed, accurate high-speed circuitry is required for controlling the flashing of the lamps.

One critical problem which has been found to occur in such devices, as well as other devices which require selective flashing, is the false flashing of lamps within the array which are usually positioned in close proximity to those lamps which are flashed. Occurrences of this nature result in a false output, thereby affecting the speed and reliability of the system.

BRIEF DESCRIPTION OF THE INVENTION

The present invention is characterized by providing trigger circuitry for such lamp arrays which is capable of providing positive high-speed triggering of such lamps and which further prevents the false firing of all those lamps in the array which have not been selected to be triggered.

The present invention utilizes, in one preferred embodiment, an SCR circuit rendered selectively conductive by logical circuitry to complete an electrical circuit including a fully charged member and the lamp to permit rapid, positive discharge of the fully charged member through the lamp in order to provide flashing. Those lamps in the array which are not selected for firing are provided with blocking components to prevent triggering of the SCRs which have not been triggered for firing the lamp. The circuit connections of the SCR and blocking member are selected so as to be adapted to emit an insignificant amount of radiation when triggered and further so as to be effectively immune from radiation resonating from adjacent connections in order to prevent false triggering. Thus, the actual triggering circuitry is capable of accurately and positively triggering only those lamps which are selected for triggering, while preventing false triggering of any of the remaining lamps.

OBJECT OF THE INVENTION

It is, therefore, one object of the present invention to provide novel triggering circuitry for lamp arrays, and the like, which is designed to provide high-speed positive triggering of those lamps within an array which are to be illuminated, while preventing false triggering of the remaining lamps within the array.

BRIEF DESCRIPTION OF THE FIGURES

This as well as other objects of the present invention will become apparent when reading the accompanying description and drawings in which:

FIG. 1 is a schematic diagram showing one lamp array in which the triggering circuitry of the present application may be employed.

FIG. 2 is a schematic diagram showing triggering circuits for a lamp array, which circuits are designed in accordance with the principles of the present invention.

DETAILED DESCRIPTION OF THE FIGURES

Referring initially to FIG. 1, there is shown therein a lamp array 10 comprised of a plurality of lamps 11-1 through 11-n, some of which have been eliminated for purposes of simplicity, it being understood that the array may be greater than 100 in number. Each lamp is comprised of an anode-electrode 13-1 through 13-n and a cathode-electrode 14-1 through 14-n. Although not shown in the figure, the cathode-electrode 14 is preferably provided with a bulb-shaped tip employed to enhance the gas discharge. The envelope of the tube may preferably be filled with xenon; however, any other suitable ionized gas may be employed. Each of the flash lamps are connected with a circuit for applying a voltage across the anode and cathode-electrodes. The circuit includes a high-voltage d-c source (not shown) which is intermittently connectable to the anode-electrodes for simultaneously charging all of the capacitors 16-1 through 16-n connected between the anode leads 13-1 through 13-n of their associated lamps and a common ground bus 15. All of the capacitors 16-1 through 16-n are fully charged by application of the voltage source. Numerical 20 designates a common bus which connects all of the trigger electrodes 17-1 through 17-n of each lamp in electrical series.

An SCR 12-1 through 12-n is electrically connected in series with each lamp 11-1 through 11-n, whereby the anode-electrode of each SCR is connected to the cathode-electrode 14 of its associated lamp and whereby the cathode-electrode of each SCR is electrically connected to ground bus 15. The trigger electrode of each SCR is connected to the output terminal of an associated gate circuit 18-1 through 18-n, respectively. In order to cause the flashing of any one or more of the lamps within the array, suitable input signals are applied to the gate circuits 18-1 through 18-n to render their associated SCRs conductive. The high-voltage d-c source is decoupled from the anode-electrode of all of the lamps and the common bus 20 simultaneously applies a trigger pulse signal to the trigger electrodes 17-1 through 17-n of all of the lamps 11-1 through 11-n, respectively. The trigger pulse enables all of the lamps to be discharged; however, only those lamps whose SCRs have been enabled will establish a closed loop current path with the SCR, the capacitor and the lamps to permit the capacitor to discharge through the lamp.

One advantageous application of such a lamp array is set forth in detail in the above-mentioned copending application, Ser. No. 801,635. The basic function of the high-speed triggering circuit is to cause selected ones of the lamps to fire as and when predetermined characters provided on the revolving drum are in registry with an associated lamp so as to cause the desired image to be projected upon a light-sensitive surface for ultimate printing of a character, or other image.

In the high-speed, non-impact printer described in the above-mentioned copending U.S. application, the lamps in the array are arranged at very closely spaced intervals such that their connecting terminals as well as the connecting terminals of associated components for each lamp, are also quite closely spaced. It has been found that the triggering operation in conventional devices causes selected leads of the trigger circuit components to generate either a magnetic or an electromagnetic field which is omnidirectional so as to activate a similar lead of an adjacent component through inductive coupling to cause the false firing of one or more lamps which were not intended to be fired at that given instant. It therefore becomes necessary to provide a triggering circuit which permits high-speed operation of the lamp array and yet prevents false triggering of all remaining lamps within the array which have not been selected for illumination at that given instant.

FIG. 2 shows a triggering circuit designed in accordance with the principles of the present invention which has been

found to be highly effective in providing for positive high-speed triggering of lamps within the array, while at the same time preventing false triggering of all remaining lamps within the array which have not been selected for illumination. The circuit 20 of FIG. 2 shows one of the array of gate circuits 18, shown in FIG. 1. For purposes of simplicity, the gate circuit is shown as having one input terminal 21. However, it should be understood that the gate circuit may also have a multiple number of inputs and be designed to operate as an AND gate in order to generate a signal at its output terminal 22 when all three inputs (for example) are simultaneously in the binary ONE state. Terminal 23 of the gate circuit is coupled to a common bus 24 for providing the gate circuit with a positive d-c level.

Output terminal 22 of the gate circuit is coupled to the base electrode of transistor T through resistor R₂. The emitter electrode of transistor T is coupled to bus 24, while the collector electrode is coupled through diode D and resistor R₃ to a minus d-c bias supply which is coupled to terminal 25. Terminal 25 is further coupled to ground potential 26 through capacitor C₁. In a like manner, the bus 24 is coupled to ground potential 26 through capacitor C₂. A capacitor C₃ is coupled in parallel across resistor R₃. The common terminal 30 connecting R₃, C₃, R₄ and D, is coupled through resistor R₄ to the trigger electrode 27 of SCR 12-1.

SCR 12-1 is coupled in series with lamp 11-1 in the same manner as was previously described with respect to FIG. 1. Likewise, capacitor 16-1 is connected in parallel across the series connected elements 11-1 and 12-1, the lower terminal of capacitor 16-1 being coupled to ground potential 26. The lead 29 extending from the cathode-electrode of SCR 12-1 is coupled to a common bus 28 which is also at ground potential. The lead extending from the trigger electrode of SCR 12-1 is coupled in common to one terminal of R₄ and capacitor C₄ whose opposite terminal is coupled to ground bus 28. It should be understood that a similar trigger circuit is provided for each individual lamp within the array wherein each trigger circuit is substantially identical in design and operation to that shown in FIG. 2.

In one practical embodiment, the bias level applied to terminal 25 is minus 4 volts. The bias level connected to bus 24 at terminal 29 is of the order of plus 5.6 volts.

The voltage level at the output 22 of gate circuit 18-1 varies between 0 and 5 volts, respectively, wherein the output level is normally at 5 volts and is abruptly changed to 0 volts when it is desired to illuminate the lamp associated with gate 18-1. In this instance, an input signal is applied to input terminal 21, causing the output level at terminal 22 to go abruptly to 0 volts, thereby causing transistor T to be conductive. The conduction of transistor T causes current to flow through resistor R₃ which develops an IR drop to raise common terminal 30 to a level of the order of plus 5 volts, which has been found to be sufficient to trigger SCR 12-1 into conduction.

Under normal circumstances, i.e., prior to the triggering of SCR 12-1, terminal 30 is maintained at a level of the order of minus 4 volts which is sufficient to maintain the SCR in its non-conductive state. In this state, capacitor C₄ is charged so that the level across its terminals is also of the order of 4 volts. In order to perform a positive and accurate triggering operation, the voltage level at lead 27 must be capable of changing from minus 4 volts to plus 5 volts in the order of 0.75 to 1.25 microseconds. Conversely, immediately after a triggering operation, capacitor C₄ must be capable of becoming fully charged within a period ranging from 20 to 500 microseconds. It has been found that the charging rate of capacitor C₄ falls well within this range.

In order to prevent any SCR 12 within the array 12-1 through 12-n from being falsely triggered, it is important that a negative bias of a sufficient level be applied to the trigger electrode. Capacitor C₄ serves this function since it is capable of being fully charged to the necessary negative bias level by way of the bias supply coupled to terminal 25 as soon as transistor T is rendered non-conductive. The voltage

developed across capacitor C₄ has been found to be sufficient to block out transients but is insufficient to block out the firing pulse. Diode D protects transistor T and the logic gate 18-1 in case a short circuit develops across lamp 11-1.

Another significant characteristic of the trigger circuit 20 shown in FIG. 2 is the use of discrete components 12-1 and C₄ whose leads are adapted to be effectively incapable of emitting significant radiation and, alternatively, being effectively insensitive to radiation emitted from the discrete components of adjacent triggering circuits. Grounded bus 28 may be considered to represent a conductive coating provided upon a printed circuit board and which is adaptable to have mounted thereon a plurality of discrete components such as, for example, SCR 12-1, capacitor C₄, transistor T, and so forth. The nature of the printed circuit boards utilized in such lamp arrays and as dictated by the compact closely spaced arrangement of the lamps in lamp array 11-1 through 11-n, necessitates a similar closely spaced arrangement for the components such as 12-1 and C₄ for each lamp 11 within the array. For example, a single printed circuit board may have mounted thereon the discrete components for as many as twenty triggering circuits. The length of the leads for discrete components 12-1 and C₄ have been found to be extremely critical. For example, the rate of change of current through capacitor C₄ and the SCR cathode lead 29 is so rapid as to cause these elements to radiate. The omnidirectional radiation, in conventional circuits, has been found to influence the leads of like components provided in the neighboring triggering circuits for associated lamps which can influence the blocking capacitor C₄ and SCR 12-i so as to cause false triggering of a lamp which is otherwise not intended to be illuminated. For this reason, it is important to select the length of the leads for capacitor C₄ and the lead 29 of SCR 12-i so that they will emit insignificant radiation and so that they conversely will be substantially insensitive to radiation emitted from like components of neighboring triggering circuits. This coupling may be referred to as the "antenna effect". The magnetic field generated by a conductor is known to be directly proportional to its length and inversely proportional to the square of the distance between the conductor and the point at which the magnetic field is being measured. Since the spacing between leads of neighboring components is limited as a result of the high packaging density of the printed circuit board, the magnetic field generated by the leads can be appreciably reduced by shortening the length of the leads.

In one practical circuit design, it has been found that the lead length between the upper terminal of capacitor C₄ and lead 27, the lead length of the lead between capacitor C₄ and ground bus 28 and the lead length of lead 29 between the cathode-electrode of SCR 12-1 and ground bus 28 was of the order of one-fourth inch. These lead lengths, coupled with the provision of blocking capacitor C₄ were found to be extremely effective in preventing false triggering of lamps within the array. As a practical matter, the lead lengths, if made too short, are extremely difficult to handle in the case where the discrete components are being mounted upon and soldered to the printed circuit board. The lead lengths can be greater than one-fourth inch and preferably should be made no greater than 1 inch in length in order to reduce the antenna effect. The lead length can be less than one-fourth inch and may be as small as one-eighth inch. Exhaustive experimentation of lamp arrays of the type described herein have shown that no false triggering will occur when utilizing the trigger circuit and design parameters described hereinabove.

It can be seen from the foregoing description that the present invention provides a novel triggering circuit for use in triggering only selected lamps within a lamp array wherein the triggering can be performed in a fast, positive manner and wherein those remaining lamps which are not to be triggered are prevented from false firing in accordance with the triggering circuit employed and the design parameters of certain critical components provided therein.

Although this invention has been described with respect to its preferred embodiments, it should be understood that many variations and modifications will now be obvious to those skilled in the art, and it is preferred, therefore, that the scope of the invention be limited not by the specific disclosure herein, but only by the appended claims. 5

1. Means for closing a normally open electrical circuit comprising

normally open switch means having first and second terminals in said electrical circuit and further including a 10 control terminal for closing said switch means;

bias means;

energy storing means coupled to said control terminal and said bias means and adapted to develop a bias level for normally maintaining said switch means in the open state; means for charging said energy storing means to said bias level; 15

second switch means coupled to said control terminal and said energy storing means and having an input terminal for receiving an input trigger signal to apply a trigger level output signal to said control terminal for rapidly overcoming said bias level and closing said switch means; 20

said energy storing means being adapted to be rapidly recharged to said bias level when said input trigger signal is removed. 25

2. Means for closing a normally open electrical circuit which includes a silicon controlled rectifier having anode and cathode electrodes connected in said electrical circuit and having a trigger electrode for rendering said silicon controlled rectifier conductive 30

a first capacitor being connected between said trigger electrode and one of said cathode and anode electrodes;

a first constant bias source connected to said trigger electrode for charging said capacitor to a bias level sufficient to normally maintain said silicon controlled rectifier in the non-conductive state; 35

transistor means having an input terminal for receiving a first input pulse signal and an output terminal connected to said trigger electrode for rapidly overcoming said bias level and triggering said silicon controlled rectifier into the conductive state in the presence of said input pulse signal; 40

said capacitor being adapted to be rapidly recharged to said bias level when said trigger pulse signal is terminated. 45

3. The circuit of claim 2 wherein said first capacitor is provided with conductive leads for connecting the first capacitor into the electrical circuit;

said silicon controlled rectifier having conductive leads for connecting the electrodes of said silicon controlled rectifier into the electrical circuit;

the conductive leads of said first capacitor and the lead of said one of said cathode and anode electrodes being of a length in the range from one-eighth to 1 inch to prevent said circuit from being falsely activated in the presence of electrical radiation which may be present in the region of said capacitor and silicon controlled rectifier leads. 55

4. The circuit of claim 3 being further comprised of a flash lamp having first and second electrodes and a trigger electrode, said first and second electrodes being connected in said electrical circuit so that said silicon controlled rectifier and said lamp are in electrical series;

said lamp trigger electrode being adapted to receive a second trigger input pulse for enabling said lamp; 60

a second capacitor connected in parallel across said series connected silicon controlled rectifier and first capacitor;

second bias means for charging said second capacitor;

said second capacitor being adapted to be discharged through said silicon controlled rectifier and said lamp when said first and second trigger input pulses are simultaneously present. 70

5. A trigger circuit for rapidly energizing selected lamps within an array wherein said array is comprised of a plurality of lamps arranged in a closely spaced manner each lamp having first, second and control electrodes;

a silicon controlled rectifier for each lamp, each of said silicon controlled rectifiers having cathode, anode and trigger electrodes;

a first capacitor for each lamp, each first capacitor being connected across the first electrode of its associated lamp and ground potential;

the second electrode of each lamp being connected to the anode electrode of its associated silicon controlled rectifier;

said silicon controlled rectifiers being arranged at closely spaced intervals;

an elongated conductive member maintained at zero potential;

each silicon controlled rectifier having a conductive lead for connecting its cathode electrode to said conductive member, all of said leads being arranged at closely spaced intervals;

a second capacitor for each lamp, each of said second capacitors having conductive leads for connecting said second capacitors between the trigger electrode of their associated silicon controlled rectifiers and said conductive member;

said second capacitors being arranged in a closely spaced fashion;

first bias means for simultaneously charging all of said first capacitors to a first predetermined voltage level;

second bias means for simultaneously charging all of said second capacitors to a second predetermined voltage level sufficient to maintain their associated silicon controlled rectifiers in the non-conductive state;

transistor means for each lamp, each of said transistor means having an input terminal for receiving a first trigger pulse and an output terminal connected to the trigger electrode of its associated silicon controlled rectifier to overcome the bias level of its associated second capacitor and thereby drive its associated silicon controlled rectifier into conduction;

means for connecting the control electrodes of all of said lamps in common and including means to receive a second trigger pulse for enabling all of said lamps to ignite whereby only those lamps whose associated silicon controlled rectifiers are triggered into conduction will be ignited. 40

6. The trigger means of claim 5 wherein the length of said second capacitor leads is within the range of from one-eighth to 1.0 inch to be insensitive to radiated energy developed by similar leads of adjacent elements which radiate energy when their transistor input terminals receive a first trigger pulse so as to prevent improper triggering of lamps which are not selected for ignition.

7. The trigger means of claim 5 wherein the length of said silicon controlled rectifier cathode lead is within the range of from one-eighth to 1.0 inch to be insensitive to radiated energy developed by similar leads of adjacent elements which radiate energy when their transistor input terminals receive a first trigger pulse so as to prevent improper triggering of lamps which are not selected for ignition.

8. The trigger circuit of claim 5 wherein each of said transistor means is comprised of a transistor having emitter, collector and base electrodes;

each of said base electrodes being connected to said transistor means input terminal;

each of said collector electrodes being connected to said transistor means output terminal.

9. The trigger circuit of claim 8 wherein each of said transistor means is provided with a third electrode means for connecting all of said third electrodes in common;

third bias means connected to said common connection means;

parallel connected resistor means and third capacitor means being connected between the output of each transistor and said second bias means.

10. The trigger circuit of claim 9 further comprising

second resistor means connected between each diode electrode and the trigger electrode of its associated silicon controlled rectifier.

11. The trigger circuit of claim 10 further comprising diode means connected between the third electrode of each transistor and one terminal of its associated parallel connected first resistor and third capacitor.
